SUCTION CLEANER

Application filed October 18, 1926. Serial No. 142,357.

This invention relates to suction cleaners.

The general purpose of the invention is to provide in a suction cleaner an improved sweeper element for effectively loosening dirt from a floor covering.

Particularly the invention has for its object the provision in the suction opening of a suction cleaner, an element against which a floor covering is adapted to be drawn by the suction and operable to impart a shaking wave motion to the floor covering to assist in loosening dirt therefrom.

A specific object of the invention is to provide in the suction nozzle of this type of cleaner a rotary element extending longitudinally with relation to the nozzle opening and having mounted for oscillatory movement preferably by eccentric mountings at its opposite ends, the eccentricity of each being herein shown substantially opposite to that of the other.

A further object of the invention is to provide on a similarly mounted element a sweeper freely rotatable thereon.

Another object of the invention is to provide a sweeper adapted to be mounted as set forth above, the brush to be tapered to a lesser diameter adjacent its ends so as to prevent too strenuous action thereof where the amplitude of eccentric movement is greatest.

The foregoing and other objects are obtained by the suction cleaners illustrated in the accompanying drawings and described below. It is to be understood that the invention is not limited to the particular forms thereof shown and described.

Of the accompanying drawings,

Figure 1 is a bottom plan of a suction cleaner embodying the invention;

Figure 2 is a section on line 2-2 of Figure 1;

Figure 3 is a detail diametral section through a modified form of rotary brush or beater;

Figure 4 is a sectional plan of another suction cleaner embodying the invention; and

Figure 5 is a section on line 5-5 thereof.

Referring to Figures 1 and 2 of the drawings, the numeral 10 designates the nozzle of a motor-operated suction sweeper. Jour-

naled in the nozzle so as to operate in the inlet 11 thereof is a combined brush and beater 12 which may be driven in any suitable manner, for example, by the central drive shown, including a belt 13 trained over a central pulley 14 on brush 12. Belt 13 may be driven from a shaft 15 by a pulley 16, shaft 15 being driven by the rotor of the suction fan (not shown).

The brush 12 is mounted with its axis at such an angle that its opposite ends are substantially eccentric in opposite directions with respect to the rotary axis of the brush defined by sleeves 17, 17 on which the brush 12 is mounted, the sleeves 17 being secured on ball bearings 18, 18 on a horizontal shaft 19 journaled in the nozzle piece 10. The ends of brush 12 are tapered as shown so as to avoid too strenuous action of these ends on the floor covering.

In Figure 3 the brush 12^a is arranged to be freely rotatable on its inclined eccentric mounting 12^b so as to have a gentler beating action, the brush tending to slip on its mounting as it strikes the floor covering.

With reference to Figure 4, it is to be noted that the advantages of the invention may be secured with the end drive type of brush or beater. In this form, a brush 20, similar to brushes 12 and 12^a, is mounted on end pieces 21 and 22 having a common horizontal axis of rotation on nozzle piece 10^a provided with oppositely eccentric threaded portions 21^a and 22^a threaded into the ends of the brush and provided with concentric pulleys 21^b and 22^b having trained thereover a belt 24 driven by pulley 16^a similar to pulley 16 and trained over pulleys indicated at 25, 26, 27 and 28.

In the use of any form of the invention, each brush, 12, 12^a or 20, is driven at a comparatively rapid rate, the floor covering being drawn upwardly by the suction against the brush which, due to its inclined mounting on oppositely directed eccentrics, has a transverse brushing, shaking and beating action back and forth on the floor covering. The movement of the brush and the suction action impart a wave motion to the floor covering in effect, shaking it to loosen the dirt, the wave motion extending

from a node at the center of the brush to nodes at considerable distances from the sides of the cleaner. It will be seen that the rug is first moved upwardly by the suction of the motor and then downwardly by the eccentrically mounted rotating brush. This makes the downward movement of the rug positive while the upward movement of the rug is not. Because of the speed of rotation of the brush 10 and the non-positive upward movement of the rug, the rug in its upward movement does not touch the brush, but lags behind. As soon however, as the eccentricity of the brush mounting again begins to move the brush 15 down, the brush and the lagging rug come together to give a distinct beat to the rug; hence in addition to the brushing and shaking actions the brush also acts as a beater.

Modifications of the invention may be resorted to without departing from the spirit thereof or the scope of the appended claims.

What is claimed is:

1. A suction cleaner including a nozzle having a suction inlet, a rotatable element 25 journaled in the inlet, the geometrical, longitudinal axis of said element being inclined to the axis of its rotation, the ends of the element being mounted substantially oppositely eccentric to said axis of rotation, and means 30 for rotating said element.

2. A suction cleaner including a nozzle having a suction inlet, means comprising a rotatable element journaled in the inlet, the geometrical, longitudinal axis of the element 35 being inclined to its axis of rotation so as to be movable in the inlet and against which a floor covering may be drawn by suction and operable to impart a shaking motion to the floor covering, the movement of the floor covering, will periodically lag behind the oscillating movement of said element, whereby said means has a beating action on the floor covering, and means for rotating said element.

3. A suction cleaner including, in combination, a nozzle piece having an elongated suction inlet, an elongated element arranged longitudinally of the inlet and journaled on the nozzle piece, said element having its geometrical, longitudinal axis at an angle to its axis of rotation, whereby it will have a shaking action on the floor covering transversely of the movement of the cleaner thereover, and means for rotating said element.

4. A suction cleaner including, in combination, a nozzle piece having an elongated suction inlet, an elongated element arranged longitudinally of the inlet and journaled on the nozzle piece, said element having its geometrical, longitudinal, axis at an angle to its axis of rotation and a freely rotatable sleeve having rug cleaning means mounted thereon concentric with its geometrical, longitudinal axis, and means for rotating said element.

5. A suction cleaner including, in combi-

nation, a nozzle piece having a suction inlet, journal means in the nozzle defining a horizontal axis of rotation in the nozzle above the inlet, an element rotatable on said journal means about said axis, the geometrical, longitudinal axis of the element being inclined to the axis of rotation, a brushing member mounted so as to be freely rotatable on said element, and means for rotating said element.

6. A suction cleaner including, in combination, a nozzle piece having a suction inlet, journal means in the nozzle defining a horizontal axis of rotation above the inlet, an element rotatable on said journal means about said axis, the geometrical, longitudinal axis of the element being inclined to the axis of rotation and intersecting the latter substantially above the center of the inlet, and means for rotating said element.

7. A suction cleaner comprising a suction nozzle having an inlet, an axle member, and a brush mounted on said axle member and filling said inlet, said brush being eccentrically mounted with respect to said axle member whereby upon rotation it will be transversely oscillated in the inlet.
